UNITED STATES PATENT OFFICE.

MIRABEAU NORMAN LYNN, OF CINCINNATI, OHIO, ASSIGNOR TO THE LYNN FILTER MANUFACTURING COMPANY, OF CINCINNATI, OHIO, A CORPORATION OF OHIO.

WATER-FILTER.

SPECIFICATION forming part of Letters Patent No. 795,047, dated July 18, 1905.

Application filed September 30, 1904. Serial No. 226,651.

To all whom it may concern:

Be it known that I, MIRABEAU NORMAN LYNN, a citizen of the United States, residing at Cincinnati, in the county of Hamilton and 5 State of Ohio, have invented a new and useful Water-Filter, of which the following is a specification.

My invention relates to that class of water-filters in which the filtering medium is a cylindrical tube of stone or artificial stone and 10 which have a scraping or cleaning device operated from the exterior without taking the filter apart.

The objects of my invention are, first, to 15 simplify the construction of this style of filter so as to have but one stuffing-joint and that always subject to compression by a stuffing-nut and to secure the outlet for filtered water at the same end of the filter at which the 20 stuffing-nut is located; second, to secure a more easily operated cleaning device or scraper of more perfect bearing upon the filtration-stone; third, a simpler and better spring by 25 which the scraping device may be kept in contact with the filtration-stone as the latter is worn to a smaller diameter by usage. I attain these objects by the mechanism illustrated in the accompanying drawings, in which—

Figure 1 is a vertical section of the entire 30 machine. Fig. 2 is a side view of the filtration-tube and scraper. Fig. 3 is a section on the line $\alpha\alpha$ of Fig. 1.

Similar letters refer to similar parts throughout the several views.

35 A is a shaft which runs through the center of the cylinder, carrying the frame E of the scraping device. α is a wheel by which the same is revolved.

B is the filtration-cylinder or filtering-tube, 40 being hollow through the center or axis.

C is the top casting, end piece, or lid.

D is the center tube through which the rod

A passes. It is threaded into the top casting or lid at d . It has a flange d' at the opposite 45 end, by means of which it holds the filter-tube to the top casting.

E is the scraper-frame, which is borne upon

the shaft A, having two arms, one of which, e , extends parallel to and one-half the length of the filter-tube. The other, e' , extends the 50 whole length of the filter-tube.

F is the exterior casing of the filter. It is provided with an inlet f and an outlet f' to permit the dirty water to flow out at the time the filter is cleaned and flushed and serves no 55 function other than as a casing for the entire machine and for that reason is not further elaborated.

G is a stuffing-nut surrounding the shaft A and threaded into the top casting at g . Its 60 purpose is the compression of the packing in the gland I and may be tightened from time to time, as may be necessary. Referring to Fig. 1 of the drawings, it will be noted that the top C has a slight inner flange adjacent to 65 the threaded part d thereof, forming a bore for the packing I larger than the diameter of the threaded part d . This larger bore receives the packing I, which latter thereby takes over the joint between the channels for the filtered 70 and unfiltered water of the casing formed by the threads d , thereby dispensing with the necessity of nicety of fit in said threaded connection. It will also be noted that this same gland I takes above the unfiltered-water passage between the shaft A and the tube D, the 75 compression of the gland I by means of the stuffing-nut G simultaneously packing the threaded joint d for preventing connection

between the respective filtered and unfiltered 80 water passages and the journal-joint between the packing-gland I and the shaft A for preventing leaking of the filter, making a highly 85 useful and economical construction. It is an important feature of this invention, as it affords a tight joint at the end of the exterior space around the center tube D, containing filtered water, and also at the end of the interior space within the said center tube and around the shaft A, making it unnecessary to 90 have a packing-gland about the shaft A at the other end thereof.

H is a duct for filtered water. The water entering the filter at f surrounds the filter-

tube B, percolates through its walls and is thereby cleansed, and is drawn out at the outlet J.

The cleansing or scraping device K is any convenient form of scraper or brush, &c., carried upon a spring L, of any suitable material, one end of which spring is securely attached to the scraper - arms e or e'. Said spring is preferably of an elongated S curve in shape. The scraper K is borne at the middle thereof, and the other end l of the spring L bears against the interior of the casting of the filter, thus keeping the scraper K always in close contact with the filtration-tube B as the latter wears smaller from usage. Two scrapers K are used, each covering one-half of the length of the filter and being on opposite ends of the cylinder from each other, by this means balancing their bearing force upon the filter-tube, tending to preserve its alignment and making the cleaning operation easier.

It has been found in practice that in long filters provided with long filtration-stones in which scrapers of the full length of the stone have been employed and in which the scrapers were turned by a wheel or crank direct on the scraper - shaft without the intervention of power-multiplying gearing great force was necessary to move the scrapers, making the same impracticable. It has also been found that to place a full-length scraper at one side of the stone only resulted in binding of the parts and consequent stiffness in movement and undue wear upon the surface of the stone. In order to overcome these objections, I provide a plurality of scrapers whose combined length shall practically equal the length of the stone and which are arranged at various points about the longitudinal axis of the stone, preferably equidistantly, thus minimizing the resistance of the scrapers, preventing their binding, providing ease of operation, and preventing undue wear upon the stone itself, thereby lengthening its life.

To clean the filter, outlet f' is opened. This permits the reverse flow of the filtered water from the reservoir, in case one is used in connection with the filter, in from the outlet J to the filtered-water duct H, percolating thence outwardly through the filter-tube B, and thus to the outlet at f', thus cleansing the interior pores of the filter-tube B at the same time the wheel is revolved, revolving the shaft A, revolving the scraper-frame E, with its prongs or forks e e', and carrying the scrapers around the filter and scraping off the accumulated mud and impurities, which fall to the bottom of the filter and are carried out through the outlet f' with the water.

Having thus described this water-filter, the features thereof that I claim as my invention, and desire to protect by Letters Patent, are as follows:

65 1. In a water-filter, the combination of a

containing vessel, a top casting, a filtration-cylinder hollow through its axis, a center tube within the hollow axis of the cylinder threaded into the top casting at one end and flanged outwardly at the other holding the filtration-cylinder in place, a filtered-water chamber surrounding said center tube, a center shaft within said center tube bearing a rotary cleaning device operated by a wheel or crank at the same end of the filter at which the stuffing-nut, filtered-water duct and top casting are located, a packing-gland and stuffing-nut about the center shaft against the threaded end of the tube, and a duct for the drawing off of filtered water at the same end of the filtered-water chamber as the said stuffing-nut and top casting and crank or wheel, substantially as set forth.

2. In a water-filter the combination of a containing vessel, a filtration-cylinder, a rotary scraper-frame, bearing two diametrically opposite arms, one of which arms is equal in length to the entire cylinder and bears a scraper of one-half said length which scrapes the upper half of said cylinder, the other of which is one-half the length of said cylinder and bears a scraper of one-half the length of said cylinder scraping the lower half of said cylinder, said scrapers being at diametrically opposite sides of said cylinder, substantially as set forth.

3. In a water-filter, the combination with a casing and filtration-cylinder extending longitudinally of said casing, of a cleaner-frame having a plurality of arms extending longitudinally of and arranged at different points about said cylinder, and cleaners of substantially less length than said cylinder, said cleaners respectively having operative connection with said respective arms and being located at different points longitudinally of and about said cylinder, substantially as described.

4. In a water-filter, the combination of a filtration-cylinder, a containing vessel therefor, a frame in said containing vessel, means for rotating said frame from outside said containing vessel, said frame embracing a pair of arms, one of which arms is substantially twice the length of the other of said arms, a pair of scrapers having connection with said arms and disposed on opposite sides of said filtration-cylinder, said scrapers respectively taking solely against opposite ends of said filtration-cylinder, substantially as described.

5. In a water-filter, the combination of a filtration-cylinder, a containing vessel therefor, a frame in said containing vessel, means for rotating said frame from outside said containing vessel, said frame embracing a pair of arms, one of which arms is substantially twice the length of the other of said arms, a pair of scrapers having connection with said arms and disposed on opposite sides of said filtration-cylinder, said scrapers respectively taking solely against opposite ends of said filtration-

cylinder, said connection of said scrapers with said respective arms consisting of springs secured at one end to said respective arms, said respective scrapers being secured to said respective springs intermediate of the ends of said springs and said springs having tail ends bearing against the inner wall of said containing vessel with resilient pressure for urging said respective scrapers against the wall of 5 said filtration-cylinder with resilient pressure, substantially as described.

6. In a water-filter, the combination with a casing and end piece therefor, said end piece having a bore and a flange at the inner end of 10 said bore, a filtering-cylinder, a securing-tube therefor threaded into said flange, a cleaner-shaft taking through said bore and tube, a packing-gland in said bore taking about said shaft and against said flange and the threaded 15 end of said tube, and a stuffing-nut for compressing said packing-gland, substantially as described.

7. In a water-filter, the combination with a casing and an end piece therefor, of a hollow 20 filtering-cylinder, a tube in the hollow there- 25

of, securing means between said tube and end piece, an operating-shaft in said tube taking past said securing means, cleaners operated by said shaft, a packing-gland taking about said shaft and against said securing means, 30 and a stuffing-nut for compressing said packing-gland about said shaft and against said securing means, substantially as described.

8. In a water-filter, the combination with a casing and an end piece therefor, a hollow filtering-cylinder, a tube in the hollow thereof for retaining it in place, said end piece having a bore and a flange at the inner end of said bore, connecting means between said flange and tube, a cleaner-shaft in said bore and tube, 35 a stuffing-nut threaded in said bore, and a packing-gland in said bore between said nut and flange, said packing-gland compressed against said shaft and connecting means by said nut, substantially as described.

Signed September 27, 1904.
